UNITED STATES PATENT OFFICE

ALFRED G. F. KUROWSKI, OF BROOKLYN, NEW YORK, ASSIGNOR TO UNDERWOOD
ELLIOTT FISHER COMPANY, OF NEW YORK, N. Y., A CORPORATION OF DELAWARE

DESIGN FOR A BRAILLE-WRITING MACHINE

Application filed February 25, 1933. Serial No. 47,309. Term of patent 14 years.

To all whom it may concern:

Be it known that I, ALFRED G. F. KUROWSKI, a citizen of the United States, residing in Brooklyn Borough, county of Kings, city and State of New York, have invented a new, original, and ornamental Design for a Braille-Writing Machine, of which the following is a specification, reference being had to the accompanying drawing, forming part thereof.

The figure is a perspective view of a Braille-writing machine, showing my new design.

I claim:

The ornamental design for a Braille-writing machine, as shown.

ALFRED G. F. KUROWSKI.
